COMB WITH LONG PRONGS

Sheldon Siegel, 1885 NE. 121st St.,
North Miami, Fla. 33161

Filed July 24, 1967, Ser. No. 7,957

Term of patent 14 years

(Cl. D86—8)

FIG. 1 is a front elevational view of the comb with long prongs;

FIG. 2 is a rear elevational view of the comb with long prongs;

FIG. 3 is a side elevational view thereof;

FIG. 4 is a top plan view of the comb with long prongs; and

FIG. 5 is a bottom plan view thereof.

I claim:

The ornamental design for a comb with long prongs, as shown.
